UNITED STATES PATENT OFFICE.

RUDOLPH L. PFEIL, OF HANFORD, CALIFORNIA.

WHEELED SCRAPER.

1,293,536.

Specification of Letters Patent. Patented Feb. 4, 1919.

Application filed June 28, 1917. Serial No. 177,609.

To all whom it may concern:

Be it known that I, RUDOLPH L. PFEIL, a citizen of the United States, and a resident of the city of Hanford, in the county of 5 Kings and State of California, have invented a new and useful Improvement in Wheeled Scrapers, of which the following is a specification.

My invention relates to an improvement in 10 wheeled scrapers for removing dirt, and more especially to those of large sizes, and has particular reference to improvements on that form of wheeled scraper for which Letters Patent No. 1,074,589 was issued on September 30, 1913, to Thomas B. Ferguson of Hanford, California. The objects of my improvements which I have invented are to retain within the scraper scoop the dirt which is being transported until it is desired to 20 dump it, which is especially desirable in transporting dirt long distances, to eliminate the portion of the axle which extends across the scoop in the scraper described in the Letters Patent referred to, to adjust the 25 draw bar or clevis to which the draft is applied so that after tipping the scraper scoop, in the readjustment of the scoop for filling it will slide into position without unusual jar, to have the scraper assembly 30 balanced so the load in the scraper scoop is carried directly over the side wheels, and other objects which will hereinafter appear.

These objects are accomplished by means of the invention hereinafter described and 35 shown on the accompanying drawing in which Figure 1 shows a side elevation of the scraper, Fig. 2 is a view of the scraper from the top, Fig. 3 is a view of a portion of the scraper from the inside of the scoop 40 showing parts thereof in section and showing a balance wheel which may optionally be placed on the scraper. Fig. 4 is a detailed view of the main scoop and auxiliary scoop showing their operative relation to 45 each other. Fig. 5 is a side view of a modified form of scraper disclosing a top view of the adjustable clevis. Fig. 6 is an enlarged view of the sliding clevis as attached to the tongue.

50 In said drawing I have indicated the main frame as A. B is the main scoop and C an auxiliary scoop. D and D' are the side wheels which carry the scraper. The main frame A consists of two pairs of beams 2 and 2^a and 3 and 3^a, one pair of which is 55 one each side of the scraper scoop B. The

rear portions of these pairs of beams are parallel and they converge toward the front, the beam 2 converging toward and being attached to beam 2^a, and the front end of 60 beam 3 converging toward and being attached to beam 3^a. The beams 2^a and 3^a converge. The converging extension of beam 2^a is designated as 2^b, and the converging extension of beam 3^a is designated as 3^b. 65 Beams 2^a and 3^a are tied together by a cross-beam 4 in front of the scraper wheels, and are tied at the rear of the wheels by a tie-beam 5. Side wheel D is supported on an axle 7 which rotates in boxes 8 and 8^a which 70 are suspended from, and attached to parallel beams 2 and 2^a, and side wheel D' is likewise supported on axle 7^a which is carried in boxes 9 and 9^a suspended from and attached to parallel beams 3 and 3^a. The 75 main scoop B is constructed with two sides, 27 and 27^a, a back 27^b, and a bottom 27^c. The bottom 27^c terminates in a cutting edge 27^d. E and E' are trunnion guides consisting of slotted members, one of which is attached to the inside face of each of the 80 parallel beams 2^a and 3^a. The slots in said guides are indicated on the drawing as 11 and 11^a. The main scoop is provided with trunnions 10 and 10^a which project from 85 the sides 27 and 27^a of the main scoop, said trunnions being carried in, and guided by slots 11 and 11^a. The slots and trunnions bear such relation to each other that when 90 the scoop is at its normal position with its bottom approximately on a horizontal plane, the trunnions 10 and 10^a are at the bottom of the slots 11 and 11^a. 13 and 13^a are draw-bars pivoted to the inside of the main scoop opposite to the trunnions 10 and 10^a. 95 These draw-bars extend toward the front of the scraper and terminate in hooks 15 and 15^a. H is a platform at the rear of the scraper frame on which the operator of the scraper can stand to manipulate it. For 100 the purpose of operating the scoop for filling and dumping I have provided a rocking shaft 17 which runs parallel with the tie-beam 5 and is journaled in bearings attached to said tie-beam, indicated as 17^a and 17^b. 105 18 is a tilting lever attached to rocking shaft 17, and is placed in a position near the platform so the operator can readily reach it. 19 and 19^a are rocker-shafts constructed to turn in bearings 20 and 20^a and 21 and 21^a. 110 22 and 22^a are arms attached to rocker shafts 19 and 19^a on the outside ends thereof. 23

and 23^a are arms attached to the outside ends of rocking shaft 17, and 24 and 24^a are connecting rods which join arms 22 and 23, and 22^a and 23^a, and transmit a synchronous movement from rocking shaft 17 to rocking shafts 19 and 19^a. 26 and 26^a are hangers pivoted at one end to the front of the sides 27 and 27^a of the main scoop, and the other end to arms 25 and 25^a. It will be noted that by this arrangement by moving lever 18 the scraper scoop can be set so it will cut into the earth, or the scoop can be raised so it will be clear of the earth and dump the scoop. 28 and 28^a are arms pivoted to the rear of frame A, having catches 36 and 36^a at one end thereof, the other ends of said arms extending backward under the platform H. The arms 28 and 28^a, and the catches 36 and 36^a bear such relation to the scraper scoop that normally they hook over the back of the scoop and prevent it from dumping. 58 is a push rod extending through the platform H and over the arms 28 and 28^a which converge directly under said push rod. When the operator desires to dump the scraper scoop the hooks 36 and 36^a are released by pushing the push-rod downward. When thus released the draft on the scraper furnishes sufficient power to dump the scoop. When the scraper is pulled into position for loading the catches 36 and 36^a prevent it from dumping until said catches are released.

The object of the auxiliary scoop C is to catch the dirt which may be shoved ahead of the main scoop when it is being loaded. This scoop is made approximately the same length as the main scoop but it is smaller in other dimensions. 51 and 51^a are trunnions, one of which is attached to each side of the auxiliary scoop near the bottom and near the cutting edge. 53 and 53^a are slotted guides in which the trunnions 51 and 51^a slide. These guides are attached to the inside of frame A to beams 2^a and 3^a. 33 and 33^a are supports to which the auxiliary scoop is hung. They are curved in the shape of a goose-neck 33^t, and have an approximately horizontal extension 33^b reaching toward the rear of the scraper. These supports are securely fastened to the frame A. Near the backward lower extension of the curve 33^t I have journaled shafts 32 and 32^a which carry crank arms 38 and 38^a and 39 and 39^a on opposite ends thereof. 30 is a rocker shaft extending parallel with tie-beam 5 the full length of the scraper, and is journaled on frame A. 31 is a lever attached to shaft 30 for the purpose of rocking it. 41 and 41^a are arms attached to the outside ends of rocker shaft 30. 42 and 42^a are connecting rods joining the outside ends of crank arms 39 and 41, and 39^a and 41^a. 45 and 45^a are connecting rods pivoted to arms 38 and 38^a, and to the sides of the auxiliary

scraper bowl. It will be noted that by these series of rockers and connecting rods by moving lever 31 the trunnions 51 and 51^a will slide in slots 53 and 53^a. These slots are curved, the center of the curve being near the outside end of horizontal extensions 33^b, to which supports 44 and 44^a are pivoted, the other ends of said supports being rigidly attached to the front ends of the sides of the auxiliary scoop. The relation of the curved slots 51 and 51^a with the hangers 44 and 44^a are such that when the trunnions 51 and 51^a are at the bottom of the guides 53 and 53^a, the cutting edges of the main scoop and auxiliary scoop are parallel, and the bottom of said scraper scoops are on approximately parallel planes. The said goose-neck curve 33^t is of such dimension that when the auxiliary scraper scoop is raised to its highest point which the travel of the trunnions in the curved guides will permit, it will not be stopped by said support 33.

34 is a balancing wheel attached to a swivel 14 which is attached to the front end of frame A. This balancing wheel is optional as on some types of scraper, especially those pulled by tractors, said balancing wheel can be dispensed with.

The extreme forward ends of beams 2^a and 3^a, noted on Fig. 6 as 2^t and 3^t, are formed parallel and are grooved to form a slideway 67. 60 is a sliding member fitted in said slideway which terminates at the forward end in a hook or loop 61 to which the draft can be applied. 62 is a clevis attached to said sliding member 60, and 63 and 63^a are links which connect the sliding member 60 with rods 13 and 13^a. This clevis has a plurality of holes, 65, 65^a and 65^b therein for the purpose of adjusting the length of the connecting links between the sliding member 60 and the trunnions of the main scoop. 66 is the bolt which attaches clevis 62 and the sliding member 60. If the connection between the trunnions and the sliding member are too short, the trunnions bind in the guide and will not slide readily into position for loading, and if the said connections are too long the trunnions will slide to the bottom of the guides with a jar. When the length is properly adjusted the trunnions slide to the bottom of the guides readily, but without unusual jar. When the scoop is being loaded, the sliding member will be at the back end of its travel, and when the scraper is dumped the frame will move back in relation to the scoop.

I claim as new and ask for Letters Patent upon:

1. In a wheeled scraper, the combination of a frame on wheels, a main scraper scoop hung within the frame, means for dumping the main scoop, and an auxiliary scoop hung within the frame with the cutting edge of

the main scoop and the auxiliary scoop opposite to each other, and means for lifting the auxiliary scoop consisting of curved slotted guides attached to the frame, trunnions attached to the sides of the scoop constructed to slide within said curved guides, an arched support attached to said frame, said arch being of such size that the auxiliary scoop will not touch it in the limit 10 of its travel, an approximately horizontal extension reaching backward from the bottom of the arch, a hanger pivoted to said extension at the center of the curve of said guides, the other end of the hanger being 15 attached to the auxiliary scraper scoop, and a rocker pivoted in said arch, a connecting rod from said rocker to the auxiliary scoop, and means for rocking said rocker, substantially as described and for the purposes set 20 forth.

2. In a wheeled scraper the combination of a frame, wheels carrying said frame, a main scraper scoop hung within the frame, means for filling and for dumping said main 25 scoop, and an auxiliary scoop hung within the frame opposite to the main scoop, so that normally the bottom of the auxiliary scoop will be on a parallel plane with the bottom of the main scoop when it is being 30 transported with a load, and so said bottoms slightly overlap, and independent means for dumping said auxiliarily scoop, substantially as described.

3. In a wheeled scraper, the combination of a frame, wheels carrying said frame, a 35 main scraper scoop hung within the frame, means for filling and for dumping said main scoop, an auxiliary scoop hung within the frame opposite to the main scoop, in such relation with the main scoop that when both 40 scoops are swung so their bottoms are approximately parallel with the ground, their cutting edges approximately meet, and independent means for dumping said auxiliary scoop, substantially as described and 45 for the purposes set forth.

4. In a wheeled scraper, the combination of a frame, wheels carrying said frame, a main scraper scoop hung within the frame, means for filling and for dumping said main 50 scoop, an auxiliary scoop hung within the frame opposite to the main scoop, in such relation with the main scoop that when both scoops are swung so their bottoms are approximately parallel with the ground, 55 their cutting edges approximately meet, and means for moving said auxiliary scoop in a position with the cutting edge of the auxiliary scoop approximately overlapping the cutting edge of the main scoop by the draft 60 power moving the scraper, substantially as described.

RUDOLPH L. PFEIL.
